TROLLING SINKER

William E. Evans, 524 N. 28th St.,
Milwaukee, Wis. 53208

Filed Mar. 26, 1974, Ser. No. 454,884

Term of patent 14 years

Int. Cl. D22—05

U.S. Cl. D22—30

FIG. 1 is a perspective view of the trolling sinker viewed from the front quarter.

FIG. 2 is a top view of the trolling sinker.

FIG. 3 is a side view of the trolling sinker.

FIG. 4 is a front end view of the trolling sinker.

FIG. 5 is a bottom view of the trolling sinker.

FIG. 6 is a rear end view of the trolling sinker.

The broken line illustrations of line coupling swivels in FIG. 3 are for environmental purposes only and are not a part of the claimed design.

I claim:

The ornamental design for a trolling sinker, as shown and described.
